UNITED STATES PATENT OFFICE

2,603,384

HOSE REEL INSTALLATION FOR TANK TRUCKS

John E. Wieschel, Milwaukee, Wis., assignor to
The Heil Co., Milwaukee, Wis., a corporation
of Wisconsin

Application May 1, 1948, Serial No. 24,513

6 Claims. (Cl. 222—71)

1

This invention relates to improvements in hose reel installations for tank trucks.

Heretofore, tank trucks such as those employed in the making of deliveries of fuel oil have been equipped with hose reels in a fixed location. Some trucks have been furnished with hose reels in a side compartment, and others have been equipped with a hose reel in a rear canbox. When a delivery is being made from a street curb to an oil tank at the front or side of a house, with the truck positioned parallel to the curb, the use of a hose reel in a side compartment of the truck is necessary so that the hose can be pulled straight out toward the point of delivery without being kinked. For other deliveries where the tank truck is to be backed up to position, then a hose reel in the rear compartment with its axis extending transversely of the truck, is preferred as this enables the hose to be pulled straight out from the rear compartment toward the storage tank to be filled. It is expensive for oil companies and the like to keep both types of tank truck on hand, and it also is troublesome as it requires special scheduling of deliveries for each particular type of truck.

It is a general object of the present invention to provide a hose reel installation for a tank truck which is so constructed as to provide for convenient selective delivery from either side or from the rear of the same tank vehicle.

A more specific object of the invention is to provide a hose reel installation wherein the reel is mounted for swinging movement on a vertical axis so that prior to delivery the axis of the hose reel may be disposed to extend either transversely of the truck or longitudinally thereof, depending upon requirements.

A more specific object of the invention is to provide in combination with a tank vehicle having a rear canbox or compartment, a hose reel mounted to normally extend transversely of said canbox and normally positioned therein so as to be enclosed by the usual rear canbox doors, said mounting including a swivel joint which permits swinging movement of the reel to a position where it projects from the rear of the canbox to permit convenient delivery from either side of the vehicle.

A still further object of the invention is to provide a construction as above described wherein there is novel means for bracing the hose reel unit in its extended position, and for guiding and supporting the unit in its swinging movement.

2

A further object of the invention is to provide a construction as above described wherein the conduit for conveying liquid from the tank to the hose on the reel has a swivel joint which is concentric with the axis for swinging movement of the hose reel unit.

A further object of the invention is to provide a construction as above described wherein the hose reel, meter, and pump may be manufactured as a unit for easy assembly in a tank truck body.

Other objects of the invention are to provide a hose reel for tank vehicles which is relatively simple in construction, which is simple to operate, and which is well adapted for the purpose described.

With the above and other objects in view, the invention consists of the improved hose reel installation for tank trucks, and all of its parts and combinations, as set forth in the claims, and all equivalents thereof.

In the accompanying drawings, illustrating one complete embodiment of the preferred form of the invention, in which the same reference numerals designate the same parts in all of the views:

Fig. 1 is a top view of the rear end of a tank vehicle showing the improved hose reel unit in a position swung outwardly from the rear canbox so that its axis extends longitudinally of the vehicle, the dot and dash lines indicating the alternative position for the reel unit, part of the vehicle at the top of the canbox being broken away;

Fig. 2 is a sectional view taken on the line 2—2 of Fig. 1; and

Fig. 3 is a vertical longitudinal sectional view through a fragment of the rear of a tank vehicle showing the hose reel in the extended position corresponding to the full line position of Fig. 1.

Referring more particularly to the drawing, the numeral 10 designates the rear portion of the body of a tank vehicle such as those used in delivering fuel oil. At the rear end of the body 10 is an opening 11 which affords access to the usual canbox or rear compartment 12 located directly behind the usual liquid tanks being carried by the vehicle. The opening may be equipped with doors 13 which are swingable on the hinge lines 14 to close the opening 11.

Mounted on the floor 15 of the canbox is a floor plate 16 having reinforcing flanges 17 and one or more intermediate stiffeners 18 interposed between the floor plate and the floor of the canbox.

Extending upwardly through the floor 15 and

through the floor plate 16 of the hose reel unit and leading from a tank within the vehicle is a liquid pipe 19. Positioned on the upper side of the floor plate 16 and suitably mounted for swivelling movement on the axis of the pipe 19 is a member 20 which is rigidly connected to a wing 21 (see Fig. 1) of a movable hose reel base 22.

The base 22 is preferably rectangular and formed from sheet metal having side flanges 23. Suitably supported for rotation beneath the hose reel base 22 and adapted to roll on the top of the floor plate 16 are rollers 24, 25 and 26. The roller 25 is positioned to roll between the floor plate 16 and the top flange 27 of an arcuate angle member guiding track 28. The latter has its lower edge suitably secured as by welding to the upper surface of the floor plate 16.

Suitably supported for rotation on end standards 29, which project upwardly from the swingable base 22, is a hose reel 30 on which a flexible hose 31 is adapted to be wound in the usual manner. As is customary with hose reels of this type, the inner end of the hose connects by means of a suitable leak-proof swivel joint with a conduit 32 which extends axially from one end of the hose reel. Thus, oil or other liquid may flow from the conduit section 32 into the hose which is wound on the reel as is well known in the art. The conduit 32 connects with one side of the usual meter 33 and the latter is mounted on the swingable base 22 for the hose reel. Also mounted on the swingable base 22 is the usual pump 34 which is in communication with one side of the meter 33. A pipe 35 extends from the suction side of the pump to the swivel joint 20 where there is a suitable rotary connection between the pipes 35 and 19 to permit leakproof swivelling movement of the hose reel unit while permitting flow of liquid from the pipe 19 into the conduits leading to the hose on the reel.

There may also be the usual by-pass connection 36 between the pipe section 32 and the pipe section 35, and said by-pass may be controlled by a hand valve 37.

The outer end of the hose is equipped with the usual nozzle 38 and, when the hose is withdrawn from the bottom of the reel, as in Fig. 3, it may be guided by a rod 39 as is customary.

Operation

In use of the improved tank truck, if a delivery is to be made by backing the truck up toward the point of delivery, then the hose reel unit may be left in the dot and dash line position of Fig. 1. The hose may then be pulled straight out from the rear of the truck.

If, however, the truck is to be located parallel to a curb to deliver to a tank which is opposite the righthand side of the truck, then the hose reel unit is swung to the full line position of Figs. 1 and 3. During such swinging movement the rollers 24 and 26 roll on the floor plate 16 and the roller 25 rolls beneath the flange 27 of the arcuate guiding track 28 and serves to brace and support the unit against downward tilting movement at its outer end when the unit is in the extended position of Figs. 1 and 3. With the hose reel in the position of Figs. 1 and 3, a side delivery from the right hand side of the truck may be made by pulling the hose directly out from the reel at right angles to the longitudinal axis of the truck. To make a delivery toward the opposite side of the vehicle, the same procedure is followed except that the nozzle 38 is brought up over the top of the reel before it is pulled out.

During delivery, the oil or other liquid being handled flows from the tank of the tank truck 10 through the pipe sections 19 and 35, through the pump 34 and meter 33, and through the pipe section 32 into the tubular reel axle and into the hose connected thereto.

It is to be noted that in the preferred construction illustrated, the meter and pump are mounted for swinging movement with the reel. This simplifies assembly and makes it possible to manufacture the entire installation as a unit.

When the tank truck is travelling from one location to another, the hose reel unit is, of course, swung to the dot and dash line position of Fig. 1 wholly within the compartment 11. In this position, the doors 13 may, of course, be swung closed in the usual manner.

Various changes and modifications may be made without departing from the spirit of the invention, and all of such changes are contemplated, as may come within the scope of the claims.

What I claim is:

1. In combination with a supporting frame, a hose reel having a dispensing hose thereon, a conduit on said frame for conducting liquid to be dispensed to said hose reel, a swingable base for said hose reel mounted for swivelling movement on said frame to provide for change in the position of the axis of said hose reel, an arcuate guiding track on said frame having a top flange and being concentric with the axis of swivelling movement of the hose reel base, and anti-friction means on said hose reel base cooperable with said flange of said arcuate track to brace the hose reel when the latter is in an outwardly swivelled position.
2. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the remaining portion of the base positioned in the compartment; and cooperating means on said floor and on the last mentioned portion of said base for supporting said base in all positions of movement thereof.
3. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the remaining portion of the base positioned in the compartment; anti-friction means for supporting said last mentioned portion of the base on said compartment floor; and means on said floor co-

operable with said anti-friction means for maintaining said base in a horizontal plane.

4. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter mounted on the other end of said base and interposed in the liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the meter supporting portion of the base positioned in the compartment; and cooperating means on said floor and on the meter supporting portion of said base for supporting said base in all positions of movement thereof.

5. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump supporting portion of the base positioned in the compartment; and cooperating means on said floor and on the pump supporting portion of said base for supporting said base in all positions of movement thereof.

6. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter and a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump and meter supporting portion of the base positioned in the compartment; and cooperating means on said floor and on the pump and meter supporting portion of said base for supporting said base in all positions of movement thereof.

- 10 6. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter and a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump and meter supporting portion of the base positioned in the compartment; and cooperating means on said floor and on the pump and meter supporting portion of said base for supporting said base in all positions of movement thereof.
- 15 6. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter and a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump and meter supporting portion of the base positioned in the compartment; and cooperating means on said floor and on the pump and meter supporting portion of said base for supporting said base in all positions of movement thereof.
- 20 6. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter and a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump and meter supporting portion of the base positioned in the compartment; and cooperating means on said floor and on the pump and meter supporting portion of said base for supporting said base in all positions of movement thereof.
- 25 6. In a tank vehicle having a rear compartment provided with a floor and with an opening accessible from the rear end of the vehicle: a hose reel having a dispensing hose thereon; a conduit in the vehicle for conducting liquid to be dispensed to said hose reel; a base on one end of which said hose reel is mounted; a meter and a pump mounted on the other end of said base and interposed in said liquid conduit, said base being mounted for swingable movement in a horizontal plane from a position within the rear compartment wherein the reel axis extends transversely of the vehicle to a position wherein the portion of the base on which the hose reel is mounted projects from the rear compartment with the reel axis extending longitudinally of the vehicle and with the pump and meter supporting portion of the base positioned in the compartment; and cooperating means on said floor and on the pump and meter supporting portion of said base for supporting said base in all positions of movement thereof.
